United States Patent Office.

WILLIAM W. REYNOLDS, OF BRANDON, VERMONT, ASSIGNOR TO THE
HOWE SCALE COMPANY.

Design No. 2,679, dated June 18, 1867.

DESIGN FOR COUNTER SCALES.

The Schedule referred to in these Letters Patent and making part of the same.

TO ALL WHOM IT MAY CONCERN:

Be it known that I, WILLIAM W. REYNOLDS, of Brandon, in the county of Rutland, and State of Vermont, have invented a new and original Design for Counter Scales; and I do hereby declare that the following is a full, clear, and exact description thereof, which will enable others skilled in the art to make and use the same, reference being had to the accompanying drawings, forming part of this specification.

This invention relates to a new and ornamental design for counter scales, such as are portable, or may be readily moved from place to place on a counter. In the accompanying sheet of drawings—

Figure 1 represents an elevation of a pair of scales of my design.

Figure 2, a vertical section of the central support or stand pertaining to the same, taken on the line xx , fig. 1.

Figure 3, a transverse section of the beam pertaining to the same, taken in the line yy , fig. 1.

Figure 4, a transverse section of the base pertaining to the same, taken in the line zz , fig. 1.

Similar letters of reference indicate like parts.

The base A and standard B are in one piece, the former projecting at equal distances from opposite sides of the lower part of the latter. The sides and ends of the base A are of cyma reversa form, as shown at a in fig. 4, with a fillet, b , at their upper and lower ends. The lower part of the standard B is a cyma reversa, as shown at c , with a fillet, d , at its lower end, while the body or main portion C is slightly conical, and is surrounded by a cap composed of two cyma rectas e e , a fillet, f , torus g , a receding flat head, h , and a fillet, i . The scale-beam D approximates to a lozenge form in its transverse section, the departure from that shape consisting of parallel plane surfaces at its upper and lower sides, as shown clearly in fig. 3. The sockets E E, at the ends of the base, which receive the guide-rods of the plates F F, on which the weights and articles to be weighed are placed, are of conical form.

Having thus described my invention, I claim as new, and desire to secure by Letters Patent—

The design for counter scales, substantially as shown and described.

WM. W. REYNOLDS.
